UNITED STATES PATENT OFFICE.

WALTER CRANE, OF LONDON, ENGLAND, ASSIGNOR TO JAMES TEMPLETON, JOHN STEWART TEMPLETON, ALEXANDER MILLAR, DANIEL HENDER-SON, LUSK YOUNG, AND ARTHUR GUTHRIE, OF GLASGOW, SCOTLAND.

DESIGN FOR CARPET.

SPECIFICATION forming part of Design No. 27,160, dated June 1, 1897.

Application filed April 19, 1897. Serial No. 632,866. Term of patent 7 years.

To all whom it may concern:

Be it known that I, WALTER CRANE, a subject of the Queen of Great Britain and Ireland, residing at London, in the county of Middlesex, England, have invented a certain new and original Design for Carpets, of which the following is a specification.

The new and original design consists, essentially, of a combination of daffodils and blue-
bells, such design to be used in the manufacture of carpets.

I claim—

The configuration of such design substantially as herein described and shown when applied to carpeting. 15

In testimony whereof I have signed my name to this specification in the presence of two subscribing witnesses.

WALTER CRANE.
